United States Patent Office.

C. H. ATWOOD, OF NEW BRITAIN, CONNECTICUT.

Letters Patent No. 70,499, dated November 5, 1867.

IMPROVED SNAP-HOOK.

The Schedule referred to in these Letters Patent and making part of the same.

TO ALL WHOM IT MAY CONCERN:

Be it known that I, C. H. Atwood, of New Britain, in the county of Hartford, and State of Connecticut, have invented a new and improved Snap-Hook; and I do hereby declare that the following is a full, clear, and exact description thereof, which will enable others skilled in the art to make and use the same, reference being had to the accompanying drawings, forming part of this specification.

This invention consists in combining a snap-hook with a plate in such a manner that the plate will serve as a protection to the snap-hook, and prevent the latter being injured by abrasion or rubbing, as is now frequently the case when the device is applied to horse-bridles, for which the invention is more especially designed, as horses are very generally addicted to the habit of rubbing their heads against posts and other fixtures when attached or hitched thereto.

The invention also consists in the mode of manufacturing the invention, as hereinafter fully shown and described, whereby a good, substantial article is sure to be obtained. In the accompanying sheet of drawings—

Figure 1 is a detached inner view of the plate pertaining to my invention.

Figure 2, an inner view of the plate and snap-hook, all complete and ready for use.

Figure 3, a section of fig. 2, taken in the line *xx*

Similar letters of reference indicate like parts.

A represents a metallic plate, which may be of malleable cast iron, having a loop, B, at one end, and a projection, C, at the opposite end, as shown clearly in fig. 1. At the inner side of this plate A there are two lugs or ears *aa*. These parts are all cast in one piece. D represents a snap, which is simply a straight bar, secured at one end between the lugs or ears *aa* by a pin, *b*, and having a spring, *c*, underneath it. The projection C is bent in curved form, as shown clearly in fig. 3, and is a hook, against the end of which the free or disengaged end of the snap D is kept in contact by the spring *c*, and it will be seen that by pressing inward said end of the snap or ring may be inserted in the hook, and, by releasing the snap, securely connected therewith.

The projection C is cast straight, or in the same plane with the plate A, for two reasons, first, convenience of casting, and second, it insures the device being manufactured of superior metal, as inferior metal would not admit of the projection C being bent in hook-form; it would break in bending.

The plate A serves as a guard or projection to the hook and snap, preventing them being injured by rubbing or abrasion, and it is ornamental without, adding very materially to the appearance of the bridle.

What I claim as new, and desire to secure by Letters Patent, is—

1. The snap-hook, constructed as described, consisting of the circular solid plate A, having loop B and lugs *aa* cast upon it, between the latter the straight bar D, pivoted and held in place against the turn-up end C by means of the spring *c*, as herein set forth, for the purpose specified.

2. The casting of the projection C with the plate A, in the same plane with the same, and then bending C in hook-form, substantially as and for the purposes specified.

C. H. ATWOOD.
